UNITED STATES PATENT OFFICE

2,508,021

BOTTLE-WASHING MACHINE

Charles L. Gerlach, Waukesha, Wis., assignor to
 Michael Yundt Company, Waukesha, Wis., a
 corporation of Wisconsin

Application November 15, 1944, Serial No. 563,490

6 Claims. (Cl. 134—57)

1

This invention relates to improvements in machines for washing bottles and similar objects, and relates particularly to machines in which the interior surfaces of the bottles are severally subjected to one or more high pressure jets of a fluid.

Bottle-washing machines generally comprise power-driven conveyors by which the bottles are carried through tanks containing cleaning solutions which are followed by tanks of rinsing water, the several tanks being at different temperatures, and the machines may include means for brushing both the inside and the outside surfaces of the bottles and subjecting both such surfaces to sprays of rinsing water and/or steam. One particularly effective form of bottle-washing machine includes high pressure jetting of the inside surfaces of the bottles by means of a mixture of air and water, and employs nozzles movable into and out of the bottles, as disclosed for example in United States Letters Patent 1,978,721, issued to Frank P. Perkins on October 30, 1934. In machines employing such structure, the conveyor moves intermittently to position each row of bottles over each of two sets of nozzles in two distinct and separate steps, and the bottles must remain in the predetermined positions while the nozzles are being raised into the bottles, during the jetting of the interior of the bottles and while the nozzles are being withdrawn from the bottles. Some variation in bottle position is permissible with relatively wide mouthed bottles, such as milk bottles, but small mouthed bottles must be positioned within relatively narrow limits. Bottle-conveyors, however, may not operate with sufficiently precise movements to secure the proper registry of the bottle mouths and the jetting nozzles during a full cycle of operation of the jetting means, and such non-registry results either in breakage of the bottles or damage to the machine and particularly to the jetting nozzles thereof.

It is therefore an object of the present invention to provide a bottle-washing machine of the type having nozzles for jetting the interiors of the bottles, with means insuring the positive positioning of the bottles relative to the nozzles.

Another object of the invention is to provide a bottle-washing machine using a washing head with jetting nozzles reciprocably movable into and out of the bottles, with adjustable means insuring registry of the mouths of the bottles with the nozzles.

Another object of the invention is to provide means for alining the mouths of bottles over

2

jetting nozzles movable into and out of the bottles during pauses in the movement of the bottles on a conveyor through a bottle-washing machine and to provide means for interrupting the operation of the machine unless the bottle mouths are adequately centered over the nozzles.

Another object of the invention is to provide a bottle-washing machine for preventing breakage of the bottles and damage to the machine due to improper positioning of the bottles relative to nozzles which are movable into and out of the bottles and in which the means are simple and inexpensive to manufacture, effective and reliable in operation, adjustable to various kinds and sizes of bottles, and durable in construction.

Objects and advantages other than those above set forth will be apparent from the following description when read in connection with the accompanying drawing in which:

20 Fig. 1 is a side elevation of a fragment of a bottle-washing machine with one side wall thereof removed for disclosure of the relationship of the structure of the present invention with other portions of the machine;

25 Fig. 2 is an enlarged side elevation of the structure of the present invention and is shown used in connection with two different sizes and shapes of bottles;

30 Fig. 3 is a view looking down on the plane of line III—III of Fig. 2;

Fig. 4 is an end view partially in elevation and partially in section on the plane of the line IV—IV of Fig. 3;

35 Fig. 5 is a side elevation of one of the structural elements of the present invention; and

Fig. 6 is an enlarged view of the safety stop in the drive for the bottle-centering means.

Referring more particularly to the drawings by reference numerals, the numeral 10 (see Fig. 3) 40 designates the side wall forming the enclosure of a bottle-washing machine supported on suitable adjustable pedestals 11. The side walls enclose means for supporting and driving an endless conveyor comprising a plurality of open-ended pockets 12 pivotally interconnected and severally adapted to receive and retain bottles 13 in that reach of the conveyor moving from the bottle-loading to the bottle-discharging end of the machine. The conveyor is driven intermittently 45 or step-by-step by suitable power means, and the various conveyor supporting and driving means are well known and need not be further disclosed herein.

The drive for the conveyor is synchronized 50 with or drives a shaft 20 extending across the

longitudinal axis of the machine and protruding from the sides 10 thereof and has mounted thereon cranks 24 and 25. The crank 24 is connected at its free end with one end of an adjustable rod 26 having its other end connected with a crank 27 mounted on a shaft 28 also extending across the machine and through the sides thereof and having a second crank 29 fixed thereon. The cranks 25 and 29 have links 30 and 31 connecting the free ends thereof with a cross head member 34, the movement of which is guided by a member 37. It will be understood that the driving connections from the end of the shafts 26 and 28 are duplicated on the opposite side of the machine and lead to a similar cross head 34. The links 30, 31, cross head 34, and so forth, are accessible through an opening or openings through the side wall 10, as shown in dotted line in Fig. 1, splashing through such openings being limited by baffles 35 and 36 even when a door or doors for such openings are ajar or swung wide open. A washing head, indicated at 38, is mounted on the cross heads 34 and has a plurality of sets of nozzles 39 and 40 extending therefrom, the structure of the washing head and the nozzles being preferably as shown in the above entitled patent and hence not further described.

In operation, the conveyor drive so positions the conveyor 12 that the bottles 13 are moved in step-by-step action to bring the mouths of two adjacent rows of bottles severally into alignment with the rows of nozzles 39 and 40. The shaft 28 being synchronized with or driven by the conveyor drive rocks and, through its connections with the cross head members 34, raises the washing head 38 to enter the nozzles 39 and 40 severally into the bottles 13. Air and water are then forced through the nozzles as described in the above patent, and the bottles are internally rinsed by the jets issuing from the nozzles.

The positions of the bottles 13 (and to some extent of the nozzles also) are determined by means now to be described. A plurality of shafts 45, 46, 47, and 48 are mounted in suitable bearings indicated at 49 (see Fig. 3) on frame members 50 of the machine. The shafts are arranged in pairs and extend across the machine parallel to each other, and the shafts of each pair are operatively joined at one end by intermeshing gear segments 53. Shaft 46 is provided with a crank 54 connected by way of an adjustable rod 55 with a crank 56 on the shaft 48. The crank 56 is also connected by an adjustable rod 57 and a crank 58 with a shaft 59 which is rocked by cam followers 60 upon movement of a cam 61 driven by or in synchronism with the conveyor drive. Movement of the shaft 59 rocks the shafts 46 and 48 in unison and, through the gear segments 53, rocks the shafts 45 and 47 severally associated therewith. The several pairs of shafts rock to the same extent but in opposite directions, that is the rocking of one of a pair of shafts clockwise rocks the other shaft of the pair counter-clockwise, and vice versa.

A plurality of fingers 62 and 63 are mounted in opposite and spaced relation axially on the shafts 45, 46, 47, and 48. The fingers are generally made as shown in Fig. 5 with a main finger body 64 having a mounting portion 65 on one end to cooperate with a separate mounting cap 66 in holding the fingers in any desired position on a shaft. The other ends of the fingers are formed as pads 67 extending at right angles to the finger body

and the finger body has an ear 68 extending laterally therefrom.

It will be seen that a finger 62 and a finger 63 are oppositely mounted relative to each other to form a pair with the pads 67 movable toward and away from each other as the pairs of shafts are rocked. Hence, the pads 67, when moving toward each other, engage the neck of a bottle 13 to make certain that the bottle mouth is centered over its particular nozzle and the ears 68 form a guide for the nozzle to maintain the movement thereof in a true vertical line. It will be evident that the shape of the fingers, the vertical displacement of the shafts from the bottle mouths, and the angular movement imparted to the shafts by the drive mechanism are predetermined to insure rotation of the fingers below the level of the bottle mouths when the conveyor is in motion.

In operation, as the washing head is moved to enter the nozzles into the mouths of the bottles, the shaft 46, for example, is rocked clockwise, and, through the gear segments 53, rocks the shaft 45 counter-clockwise to bring the pads 67 into holding engagement with a bottle neck (Fig. 2 shows the fingers just prior to engagement with the bottle neck for the purposes of clarity in illustration). The nozzles 39, for example, now severally move up between each pair of fingers 62, 63, and within the space defined by the ears 68 of each pair of fingers. The ears 68 thus prevent displacement of the nozzles from a predetermined line which might cause forceful contact between the nozzles and the bottles.

Continued operation of the machine, when the bottle-centering means is not in proper operating conditions, is prevented by a safety stop associated with the drive rod, generally designated 51, for such means. The rod 51 is made in two parts with a hollow rod part 72 into which a rod part 73 extends. The two rod parts are normally held in a predetermined telescoped relation by a roller 74 mounted on one end of a bell crank 75 and urged by a spring 76 to move through a slot in the rod section 72 and into a roller seat formed in the rod section 73. As long as the roller 74 remains in the seated position shown, the one of the bell crank 75 is held out of contact with a roller 80 mounted on the operating element of an electric limit switch of known construction and indicated at 81. Upon the occurrence of jamming or any other abnormal condition of the bottle-centering means, the exertion of force on the crank 58 in either direction causes the rod portion 73 to move relative to the rod portion 72 which moves the seat in the rod portion 73 out of the position shown. The roller 74 then rides up on the rod 73 and tilts the crank 75 against the action of the spring 76. Tilting of the crank 75 presses its arm against the limit switch operating roller 80 to open the mechanism of the switch 81 and thereby interrupt an electric circuit for driving the bottle-centering means or the entire machine as may be desired. As soon as the condition resisting movement of the bottle-centering means has been eliminated, the rod portion 73 resumes its former position in the rod portion 72 and the roller 74 again seats so that the switch 81 may reclose its circuit.

It will thus be seen that the present invention provides means for positively positioning bottles of various shapes and sizes, particularly when bottles are used in pockets for a larger size bottle, relative to the nozzles of a washing head for internally rinsing the bottles. Such means includes a plurality of pairs of shafts extending

parallel to each other under the bottle-carrying portion of the conveyor and over the reciprocating washing head. The shafts are rocked in unison and the shafts of each pair rock in opposite directions. The fingers are so mounted on each pair of shafts that adjacent fingers on such shafts form operating pairs movable toward and away from each other for positioning the bottles and releasing the bottles respectively. The means for reciprocating the washing head and its rows of nozzles, and the means for operating the finger-carrying shafts, are preferably driven from the bottle conveyor drive but in any event are synchronized with the conveyor movement.

Although but one embodiment of the present invention has been illustrated and described, it will be apparent to those skilled in the art that various changes and modifications may be made therein without departing from the spirit of the invention or from the scope of the appended claims.

I claim:

1. In a bottle-washing machine of the type having a power-driven conveyor positioning the bottles substantially over jetting nozzles movable into and out of the bottles, a pair of shafts mounted adjacent the conveyor, means interconnecting the shafts for rocking movement in unison and in opposite direction upon movement of one of the shafts, a plurality of fingers mounted on the shafts for coaction in pairs to engage and center the bottle mouths over the nozzles upon rocking of the shafts, means connecting the shafts with the conveyor for movement thereby and inserting means for interrupting the transmission of power to the shafts from the conveyor upon resistance of the shafts to movement.

2. In a bottle-washing machine of the type having a power-driven conveyor positioning the bottles substantially over jetting nozzles movable into and out of the bottles, a pair of shafts mounted adjacent the conveyor, means interconnecting the shafts for rocking movement in unison and in opposite direction upon movement of one of the shafts, a plurality of fingers mounted on the shafts for coaction in pairs to engage and center the bottle mouths over the nozzles upon rocking of the shafts, means connecting the shafts with the conveyor for movement thereby and including a plurality of telescopic rod portions, and means retaining the rod portions in fixed position relative to each other until shaft resistance to movement rises above a predetermined value.

3. In a bottle-washing machine of the type having a power-driven conveyor positioning the bottles substantially over jetting nozzles movable into and out of the bottles, a pair of shafts mounted adjacent the conveyor, means interconnecting the shafts for rocking movement in unison and in opposite direction upon movement of one of the shafts, a plurality of fingers mounted on the shafts for coaction in pairs to engage and center the bottle mouths over the nozzles upon rocking of the shafts, means connecting the shafts with the conveyor for movement thereby and including telescopic rod portions, and a roller urged into position to hold the rod portions in non-telescoping relation until the shafts resist movement by a predetermined amount.

4. In a bottle-washing machine of the type having a power-driven conveyor positioning the bottles substantially over jetting nozzles movable into and out of the bottles, a pair of shafts mounted adjacent the conveyor, means interconnecting the shafts for rocking movement in unison and in opposite direction upon movement of one of the shafts, a plurality of fingers mounted on the shafts for coaction in pairs to engage and center the bottle mouths over the nozzles upon rocking of the shafts, means connecting the shafts with the conveyor for movement thereby and including telescopic rod portions, a roller pivotally mounted on one of the rod portions for interengagement with and disengagement from a seat in another of the rod portions for retaining the rod portions in non-telescoping relation until the shafts resist movement thereby by a predetermined amount, and a spring acting on the roller mounting to urge the roller toward engaged position.

5. In a bottle-washing machine of the type having a power-driven conveyor positioning the bottles substantially over jetting nozzles movable into and out of the bottles, a pair of shafts mounted adjacent the conveyor, means interconnecting the shafts for rocking movement in unison and in opposite direction upon movement of one of the shafts, a plurality of fingers mounted on the shafts for coaction in pairs to engage and center the bottle mouths over the nozzles upon rocking of the shafts, means connecting the shafts with the conveyor for movement thereby, means including a plurality of relatively movable rod portions for transmitting power from the conveyor to the shafts, and means for interrupting power supplied to the conveyor upon resistance of the shafts to movement.

6. In a bottle-washing machine of the type having an electric power-driven conveyor positioning the bottles substantially over jetting nozzles movable into and out of the bottles, a pair of shafts mounted adjacent the conveyor, means interconnecting the shafts for rocking movement in unison and in opposite direction upon movement of one of the shafts, a plurality of fingers mounted on the shafts for coaction in pairs to engage and center the bottle mouths over the nozzles upon rocking of the shafts, means connecting the shafts with the conveyor for movement thereby including a plurality of relatively movable rod portions for transmitting power from the conveyor to the shafts, means for retaining the rod portions against relative movement until the shafts resist rocking by a predetermined amount, and a switch for interrupting the supply of power to the conveyor upon release of the rod portions for relative movement therebetween.
